UNITED STATES PATENT OFFICE.

EDWARD B. HESS, OF NEW YORK, AND LEWIS C. MYERS, OF BROOKLYN, NEW YORK,
ASSIGNORS TO ROYAL TYPEWRITER COMPANY, INC., OF NEW YORK, N. Y., A COR-
PORATION OF NEW YORK.

TYPE-WRITING MACHINE.

1,284,682.

Specification of Letters Patent. Patented May 27, 1919.

Application filed December 13, 1918. Serial No. 266,530.

To all whom it may concern:

Be it known that we, EDWARD B. HESS and LEWIS C. MYERS, citizens of the United States, and residents, respectively, of the 5 borough of Manhattan, in the city, county, and State of New York, and of the borough of Brooklyn, in the city and State of New York, county of Kings, have invented certain new and useful Improvements in Type-writing Machines, of which the following is a specification.

The present invention relates generally to typewriting machines and has more particularly reference to improved margin controlling devices.

The main object and feature of this invention is to render the margin controlling devices visible and readily accessible to the operator and consists broadly in arranging 20 supporting means, such as a margin rail, for margin stops adjacent the front of the platen and in so articulating the type bars that when they reach an upright position in contact with a common printing center on 25 the platen, the margin rail will be between the plane of the type bars and a vertical line drawn through the axis of the platen. This margin rail is also located intermediate the plane of the type guide and ribbon vibrator 30 and a vertical line drawn through the axis of the platen.

Other features of construction will appear as the specification proceeds:

The invention is embodied in the accompanying drawings in which:

Figure 1 is a top plan view, partly in section, indicating, in more or less diagrammatic form, the general construction of the machine to which the invention is here applied; the margin controlling devices being here in the form of a continuous rail extending across the longitudinal center line of the machine and carrying two margin stops that coöperate with a center stop at the front 45 of the platen. In this figure are also shown the type guide and ribbon vibrator located in front of the margin rail; four of a series of type bars being indicated, three in a forwardly recumbent position and one in printing position. The platen and keyboard are omitted.

Fig. 2 is a front elevation of Fig. 1 with the dust sheds in section, the ribbon spools removed and certain parts broken away, and

shows more particularly the location of the 55 ribbon vibrator and central type bar guide in front of the margin rail, a type bar being in printing position.

Fig. 3 is a top plan view largely diagrammatic in character, with parts omitted and 60 broken away and shows more particularly the relation of the margin rail and stop elements to the bell ringing and line locking and releasing means at the right hand side of the machine.

Fig. 4 is a side view of the machine, partly in section and partly broken away, with elements omitted to illustrate the relation of the margin controlling devices to the bell ringing, line locking and releasing mechanism, the parts being in normal position except one type bar that is in printing position.

Fig. 5 is a detail view of part of the elements of Fig. 4, showing the action of the 75 line lock releasing means, the carriage being in its lower case position.

Fig. 6 is a detail view of the parts in the upper right hand corner of Fig. 5 showing the margin rail in its lowered position, the 80 right hand margin stops in end elevation, and the center stop on the carriage behind the right hand margin stop.

Fig. 7 is a fragmentary plan view of the complementary stops and their supporting 85 means, together with the connections to the bell ringing and line locking means.

Fig. 8 is a front elevation of the parts shown in Fig. 7.

Fig. 9 is a fragmentary sectional view 90 showing the margin rail tilted by the action of the center stop.

Fig. 10 is a fragmentary sectional view showing the margin rail in its lowered position and the center stop between the first 95 and second dogs of the left hand margin stop.

In Figs. 11 to 17 is shown a modified form of the invention in which two stop members, one at either end of the carriage, are 100 used in place of the center stop construction shown in the preceding figures.

Fig. 11 is a plan view similar to Fig. 1 showing the modified form of the invention.

Fig. 12 is a front view similar to Fig. 2, 105 of the form of the invention shown in Fig. 11.

Fig. 13 is a fragmentary plan view of the

stop elements at the right hand end of the machine of Fig. 11, parts being broken away and in section and the connections to the bell ringing and line locking mechanism 5 being indicated.

Fig. 14 is a part end and part sectional view of the parts shown in Fig. 13.

Fig. 15 is a section on line 15—15 of Fig. 14.

Fig. 16 is a fragmentary front view partly in section of the right hand end of the margin rail and adjacent elements.

Fig. 17 is a fragmentary side view partly in section of the left hand margin controlling devices.

1 indicates the general frame-work of the machine in which is mounted the carriage raceway 2 supporting the carriage 3 and provided with case shifting mechanism indicated by the member 4 so that the carriage and its support may be raised or lowered in a manner well understood in the art. The shift mechanism employed is that of the well known Royal typewriter, such as is described in Patent No. 1,927,438. Mounted in the carriage 3 is a platen 5 of any suitable construction and provided with a suitable line space advancing mechanism 6 in the usual manner. 7 indicates a segment on 20 which are pivotally supported type bars 8 normally occupying a forwardly recumbent position with their free ends resting on a head rest 9 located near the forward end of the machine. 10 indicates the key 25 levers pivotally supported at 11 in a suitable bearing and connected by means of a vertical link 12 to a front link 13 connected to the rear of a type bar by means of a link 14. To link 14 is secured a bar or link 15, the 30 rear end of which is bent to engage a universal bar 16, link 15 being provided with a spring 17, the rear end of which is connected with an adjustable rocking frame 18 and the front end of which is secured to a member 19 carried by link 14. It will be understood that all the type bars, when actuated, move to a common printing point or center. Adjacent to the common printing point of 35 the machine is a type bar guide 20 consisting of two converging members suitably mounted by means of a bracket 21 on a stationary part of the machine. Mounted to move with the carriage raceway 2, so as to partake of the case shifting movement imparted thereto, is a ribbon vibrator 22 also located adjacent to the printing point. Inclosing the upper part of the machine are dust sheds 25 carrying ribbon spools 26.

27 indicates a margin rail extending transversely across the longitudinal center line of the machine and conveniently supported, in this instance, on top of dust sheds 25 in front of a vertical line and below a horizontal line drawn through the axis of the 45 platen; and more specifically in front of a

vertical line tangent to the front face of the platen and below a horizontal line tangent to the underside of the platen. This margin rail is located in rear of type guide 20 and ribbon vibrator 22 and in front of the 50 platen but closely adjacent thereto and extending parallel therewith.

It will also be seen that this margin rail is so located that it is above the series of type bars and slightly in rear of their pivots 55 so that it will not prevent engagement of the type bars with the platen at a common printing center, as shown more particularly in Figs. 1, 2 and 4, the location of the margin rail and the articulation of the type bars being such that when a type bar has reached the limit of its upward movement toward the platen, as indicated in Fig. 4, it will be in front of the margin rail with its type face above the margin rail and in engagement with the platen at the printing point.

This margin rail has imparted to it, during the normal traverse of the platen in a left hand direction, two successive motions of different character. Any suitable means may be employed to effect this but, in the present instance, the construction is substantially that disclosed in connection with one of the margin rails of application filed March 23, 1918, Ser. No. 224,178. To this end, the margin rail is provided with pivot extensions 31 that project into suitable bushings 32 in a stationary part of the frame-work in such manner that the margin rail has both a rocking and a lengthwise 100 sliding motion. Extending from the lower side of rail 27 is a dependent controlling member 33 and attached at one end to said controlling member is a spring 37, the other end of which is anchored on dust shed 25, 105 said spring tending normally to maintain the margin rail in normal position,—that is to say, in its extreme position to the right, lengthwise, and in its lowered position with respect to its rocking motion. This spring therefore serves a double purpose, as indicated above. 38 indicates a line lock blade carried by a laterally extending bar 39 and normally out of the plane of locking surface 40 of key levers 10, as shown in Fig. 115 5, being urged into this position by a spring 41 anchored at one end 42 to the frame work and having its other end connected to member 43 of bar 39. 44 indicates a stop to limit the downward movement of said line locking blade. Interposed between the controlling member 33 and the member 43 are suitable connections, which in the present instance, take the following form: 45

indicates a vertically extending rock shaft located below the dust shed and adjacent to the right hand side of the machine, being carried in suitable brackets, as 46. Connected to the lower end of said rock shaft 45 is an arm 47 between which and the member 120 125 130

43 is interposed a link 48. Secured to the upper end of rock shaft 45 is a bifurcated member 34 the outer end of which embraces controlling member 33. 49 is a margin release rod supported in bearings 50 and normally urged outwardly by means of a spring 51. This margin release rod carries at its inner end a pusher 49'. 52 indicates a bell suitably mounted within the machine on tie plate 53; and 54 is a hammer for the bell suitably attached to controlling member 33, as shown. 28 and 29 indicate two margin stops adjustably mounted on margin rail 27, the uninterrupted margin rail admitting of adjustment of said stops across the longitudinal center line of the machine. 30 is a center stop attached to the carriage by means of screw 100 and so arranged that it extends adjacent to the front 20 of the platen. Stop member 28 is provided with two dogs or cam members 62 and 63 projecting inwardly toward the platen and spaced apart laterally, as shown. Said dogs are provided with a taper or cam surface 25 62' and 63' which are inclined in opposite directions away from each other. Dog 63 also has an abutment surface 63''.

As the carriage moves to the left and approaches the end of its stroke as determined 30 by the position of stop element 28, center stop will engage with cam surface 62' thereby tilting margin rail 27 without effecting endwise movement thereof. As soon as center stop 30 has passed beyond the high 35 point of taper surface 62', margin rail 27 will be abruptly released thereby permitting spring 37 to restore the parts to normal position. The rocking of margin rail 27 by means of center stop 30 engaging the taper 40 surface 62' will cause the parts to assume the position shown in Figs. 9 and 5 where, it will be seen, controlling member 33 is moved into an inclined position lifting bell hammer 54. It will be noted, that in assuming 45 this position, the member 33 is free to move through the bifurcated portion of arm 34 of vertical shaft 45. On the abrupt release of margin rail 27 by the passage of center stop 30 over the high point of taper 50 surface 62', gravity and the action of spring 37 will cause hammer 54 to descend quickly, thus sounding gong 52 and thereby informing the operator that the carriage is approaching the end of the line. The carriage 55 now continues its movement to the left and center stop 30 encounters the abutment surface 63'' thereby imparting a lengthwise sliding movement to margin rail 27 and, consequently, also to controlling member 33. 60 The effect of this is that said controlling member 33 will carry the bifurcated end of arm 34 with it thereby rocking the upright shaft 45 and causing arm 47 to exert a pull on connection 48 of sufficient amplitude 65 to bring the line lock blade 38 beneath

locking surfaces 40 of the key levers. The position that the parts occupy at this time is indicated in Fig. 3. It is now impossible to manipulate the key levers to bring the type bars to the printing point and the carriage has reached the end of its movement as determined by the position of margin stop 28. If, however, it is desired to release the parts to admit of writing additional matter on the same line, the margin release rod 49, having on its inner end the pusher 49', is moved inwardly, as indicated in Fig. 5, being thus caused to engage controlling member 33 and thereby impart a rocking motion to margin rail 27 of sufficient amplitude to permit center stop 30 to pass over the high point of abutment member 63''. It will thus be seen, that the rocking motion of the margin rail has two functions, one to ring the bell and the other to release the complementary stop elements from each other when in the position described. As soon as the parts have been thus released, the pull of spring 37 will cause margin rail 27 to have a retrograde lengthwise movement thereby avoiding the necessity of keeping the margin release rod depressed. It will be understood that the margin rail 27 in being rocked for the purpose of releasing the stop elements will have 95 raised hammer 54 and, to prevent the gong from striking the bell a second time during the cycle of the machine, a taper surface 63' is provided which, as the carriage continues its movement in a left hand direction, 100 gradually permits spring 37 to restore the margin rail to normal position so far as its rocking movement is concerned. The descent of hammer 54 is therefore so gradual that no sound is heard when it finally reaches bell 52. The carriage may now, of course, be advanced to the left until the usual stop elements, not shown, come together. It is a characteristic feature of 105 this construction that the connection between the line locking means and the margin rail is always complete for the purpose of transmitting the endwise motion of said margin rail to the line locking means but that, nevertheless, the independent rocking 110 motion of the margin rail is possible for the purpose of bell ringing without affecting the position of the line locking means; also that this rocking motion is utilized for the purpose of releasing the abutment surface 115 63'' and center stop 30 so as to admit of a retrograde endwise movement of the margin rail and thereby permit the line lock to restore itself. It will be observed that with the construction disclosed, it is immaterial 120 whether the carriage is in its lower case position, as indicated in Fig. 5, or in its shifted position, as indicated in dotted lines in Fig. 6, since, in either event, center stop 30 will engage in a manner previously described 125 130

with dogs 62 and 63. It has been pointed out how engagement of center stop 30 with margin stop 28 limits the traverse of the carriage to the left of the machine in the manner described, and it will be understood that engagement of center stop 30 with margin stop 29 limits the right hand traverse of the carriage. The scale indication on margin rail 27 corresponds to the usual letter space indication.

In the modification shown in Figs. 11 to 17, the location of the margin rail and the train of connections from the margin rail 27' to the bell ringing and line locking and releasing mechanism is the same as that described in connection with the form shown in Figs. 1 to 10. In the form of the modification shown in Figs. 11 to 17, there are employed end stops 64 and 75 on the carriage instead of center stop 30. Furthermore margin stop 28' is here located at the right hand side of the machine and margin stop 29' is located at the left. It will be understood that in this form of the invention, margin rail 27' need not be continuous but is made so merely for convenience. In order to give margin stops 28' and 29' a full range of adjustment, margin rail 27' is about twice the length of rail 27, and carries a complete letter space indication on each side of the printing center, as shown, the lowest scale indication being at the right on each side of the printing center.

When the carriage approaches the end of its traverse to the left, stop member 64 encounters successively taper surface 62' and abutment surface 63'' thereby effecting bell ringing and line locking. If the line lock releasing means are actuated stop member 64 will descend on taper surface 63' without bell ringing. When the carriage is drawn to the right, member 64, which is in the form of a pivoted latch yielding in one direction as shown, will turn on its pivot in passing over dogs 63 and 62.

The right hand traverse of the carriage is limited by engagement of stop member 75 with margin stop 29' as will be understood. Stop member 75 is slidingly mounted as shown in Fig. 17 and may be retracted out of the path of margin stop 29'.

We claim:

1. A typewriting machine comprising: printing elements including a transversely movable carriage having a platen and a plurality of individually actuated type bars so articulated with respect to the platen that they occupy, when actuated, an upright position in contact with a common printing center on said platen, and margin controlling devices including: transversely extending supporting means independent of the carriage adjacent the front of the platen and in rear of the plane of the upright posi-

tion of the type bars, and complementary stop elements on the supporting means and carriage.

2. A typewriting machine comprising: printing elements including a transversely movable carriage having a platen and a plurality of individually actuated type bars so articulated with respect to the platen that they occupy, when actuated, an upright position in contact with a common printing center on said platen, and margin controlling devices including: a margin rail extending across the longitudinal center line of the machine adjacent the front of the platen and in rear of the plane of the upright position of the type bars, and complementary stop elements on the supporting means and carriage. 75

3. A typewriting machine comprising: printing elements including a transversely movable carriage having a platen and a plurality of individually actuated type bars so articulated with respect to the platen that they occupy, when actuated, an upright position in contact with a common printing center on said platen; and margin controlling devices, including: a margin rail extending across the longitudinal center line of the machine adjacent the front of the platen and in rear of the plane of the upright position of the type bars, stop elements on the margin rail adjustable across said center line, and a stop on the carriage adjacent the front, and at the center, of the platen. 85

4. A transversely movable carriage having a platen, a type guide in front of the platen and adjacent the printing center of the machine, and margin controlling devices adjacent the front of the platen and intermediate the latter and the plane of the type 100 guide. 105

5. A transversely movable carriage having a platen, a ribbon vibrator in front of the platen and adjacent the printing center of the machine, and margin controlling devices adjacent the front of the platen and intermediate the latter and the plane of the 110 ribbon vibrator.

6. A transversely movable carriage having a platen, a type-guide and a ribbon vibrator in front of the platen and adjacent the printing center of the machine, and margin controlling devices adjacent the front of the platen and in rear of the plane 115 of the type guide and ribbon vibrator. 120

7. A transversely movable carriage having a platen, a type guide and a ribbon vibrator in front of the platen and adjacent the printing center of the machine, and a margin rail in rear of the plane of the type 125 guide and ribbon vibrator and in front of the platen.

8. A typewriting machine comprising: a

- transversely movable carriage having a platen, a margin rail in front of, closely adjacent to and parallel with the platen and carriage extending across the longitudinal center line of the machine, a plurality of normally forwardly recumbent type bars, in front of the platen, carriage and margin rail, so articulated with respect to the platen and margin rail as to reach, when actuated, a common printing center on the platen above the margin rail, stop elements on the rail adjustable lengthwise thereof and across the longitudinal center line of the machine, and a margin stop on the carriage adjacent the front, and at the center, of the platen.
9. A typewriting machine comprising: printing elements including a transversely movable carriage, having a platen, and a plurality of normally forwardly recumbent type bars in front of the platen and carriage, a type guide adjacent the printing point of the platen, and visible margin controlling devices adjacent the front of the carriage and platen and in rear of the plane of the type guide including transversely extending supporting means independent of the carriage, and complementary stop elements on the supporting means and carriage.
10. A typewriting machine comprising: printing elements including a transversely movable carriage, having a platen, and a plurality of normally forwardly recumbent type bars in front of the platen and carriage, a ribbon vibrator adjacent the printing point of the platen, and visible margin controlling devices adjacent the front of the carriage and platen and in rear of the plane of the ribbon vibrator including: transversely extending supporting means independent of the carriage, and complementary stop elements on the supporting means and carriage.
11. A typewriting machine comprising: printing elements including a transversely movable carriage having a platen, and a plurality of normally forwardly recumbent type bars in front of the platen and carriage, a type guide and a ribbon vibrator adjacent the printing point of the platen, and visible margin controlling devices adjacent the front of the carriage and platen and in rear of the plane of the type guide and ribbon vibrator including transversely extending supporting means independent of the carriage, and complementary stop elements on the supporting means and carriage having a platen, a margin rail in front of, closely adjacent to and parallel with the platen and carriage extending across the longitudinal center line of the machine, a plurality of normally forwardly recumbent type bars, in front of the platen, carriage and margin rail, so articulated with respect to the platen and margin rail as to reach, when actuated, a common printing center on the platen above the margin rail, stop elements on the rail adjustable lengthwise thereof and across the longitudinal center line of the machine, and a margin stop on the carriage adjacent the front, and at the center, of the platen.
12. A transversely movable carriage having a platen, a type guide in front of the platen and adjacent the printing center of the machine, and a margin rail interposed between the type guide and platen and in front of a vertical line and below a horizontal line drawn through the axis of the platen.
13. A transversely movable carriage having a platen, a ribbon vibrator in front of the platen and adjacent the printing center of the machine, and a margin rail interposed between the ribbon vibrator and platen and in front of a vertical line and below a horizontal line drawn through the axis of the platen.
14. A typewriting machine comprising: printing elements including a transversely movable carriage having a platen and a plurality of normally forwardly recumbent type bars so articulated with respect to the platen that they occupy, when actuated, an upright position in contact with a common printing center, and a margin rail in front of, closely adjacent and parallel with the platen and carriage extending across the longitudinal center line of the machine and in rear of the plane of the upright position of the type bars.
15. A typewriting machine comprising: printing elements including a transversely movable carriage having a platen and a plurality of normally forwardly recumbent type bars so articulated with respect to the platen that they occupy, when actuated, an upright position in contact with a common printing center on said platen, transversely extending supporting means independent of the carriage between the plane of the pivotal point of the type bars and a vertical line drawn through the axis of the platen and above said pivotal point and below a horizontal line drawn through the axis of the platen, and complementary stop elements on the supporting means and carriage.

Signed at the borough of Manhattan, city, county and State of New York, this 12th day of December 1918.

EDWARD B. HESS.
LEWIS C. MYERS.
